CLAIM

The ornamental design for a microwave roasting rack
or the like, as shown.

DESCRIPTION

FIG. 1 is a top perspective view of a microwave roasting
rack or the like showing our new design;

FIG. 2 is a top plan view thereof;

FIG. 3 is a front elevational view thereof, the rear view
being a mirror image;

FIG. 4 is a bottom plan view thereof; and

FIG. 5 is a side elevational view thereof.

FIG. 2

FIG. 3

FIG. 5

FIG. 4
